UNITED STATES PATENT OFFICE.

HENRY L. BONNEY, OF NORTH ANDOVER, MASSACHUSETTS, ASSIGNOR TO THE DAVID BROWN COMPANY, OF LAWRENCE, MASSACHUSETTS, A CORPORATION OF MASSACHUSETTS.

AUTOMATICALLY-THREADING SHUTTLE.

Application filed February 19, 1925. Serial No. 10,406.

To all whom it may concern:

Be it known that I, HENRY L. BONNEY, a citizen of the United States, and resident of North Andover, in the county of Essex and State of Massachusetts, have invented an Improvement in Automatically-Threading Shuttles, of which the following is a specification.

This invention relates to that class of shuttles employed in automatic looms, which are threaded automatically when a fresh bobbin is placed therein, the threading operation being partly performed on the first pick, after the bobbin is inserted, which causes the 10 thread to be drawn in line with the shuttle over the bobbin tip, and the operation being finished on the next pick when the thread is drawn into the shuttle eye.

In shuttles of this character, in the present stage of development there is little or no difficulty due to unthreading after the thread has been drawn into the shuttle eye, but practically the whole difficulty due to unthreading arises at the beginning of the second pick. This is usually due either to the fact that the thread is not drawn into the thread slot past the thread retaining means, so that there is nothing to prevent unthreading when the shuttle is started on the second 20 pick, or to failure of the thread-retaining means to perform its function under all conditions. Failure to perform the first stage of the threading operation is often due to the fact that, as the bobbin is then full, the thread frequently comes off the bobbin very 25 easily and is often so slack that it is placed under little or no tension, or at least insufficient tension to draw it into the thread slot, past the thread retaining means which 30 is employed, the entrance to the slot being often more or less obstructed by deflecting surfaces past which the thread must be drawn to pass therein. That is, while most 35 of these devices will thread properly when the thread is placed under sufficient tension, many of them fail to thread when the thread is not drawn taut.

In shuttles of the above described type now in general use, the threading slot is either formed in the metal threading block, or one side of the slot is formed by the wood of the shuttle and the other side by the

block, and with the latter type difficulty has been encountered due to the closing of the slot by reason of the springing of the wood from various causes, while with the other type difficulty is encountered due to breakage of castings or bending of the sides of the slot so as to catch the thread by the tightening action of the screw employed to hold the block in position in the shuttle, or to the presence of metal deflecting surfaces which offer too great obstruction to the passage of the thread into the first threading position.

The objects of my invention are to provide an automatically threading shuttle which is so constructed that the preliminary threading operation, which takes place during the first pick, will be fully completed under practically all conditions and even if the pull on the thread is insufficient to draw it taut or more than to lay it into the entrance to the threading slot, so that it may fall therein, into such a position that it will be positively retained in position to permit the threading operation to be completed on the next pick. Also to provide thread retaining means which will effectively prevent unthreading after the thread has passed into the preliminary threading position.

A further object of my invention is to provide a form of threading block having a threading slot therein having walls or sides which are rigidly held, so that liability that the slot will be closed sufficiently to catch the thread by yielding of the shuttle wood, or by the tightening action of the securing bolt, or from other causes will be practically eliminated.

I accomplish these objects by means of the construction hereinafter described and illustrated in the accompanying drawing in which:—

Figure 1 is a top plan view of the thread delivery end portion of an automatically threading shuttle embodying my invention.

Figure 2 is a transverse section thereof at lines 2—2 of Figure 1.

Figure 3 is a side elevation thereof.

Figure 4 is a side elevation of the threader with the wood of the shuttle in section.

Figure 5 is a cross section at line 5—5 of Fig. 1.

Figure 6 is a front end view of the threader.

Figure 7 is a bottom view thereof.

Figure 8 is a sectional view at line 8—8 of

5 Figure 6.

Figure 9 is a sectional view at line 9—9 of Figure 3.

Figure 10 is a perspective view of the thread delivery end of the shuttle.

10 Figure 11 is a front end view of a slightly modified form of threader.

As shown in the drawing, the shuttle body 10 is provided with the usual chamber 11 in which the bobbin 11¹ is held, and the slotted side delivery eye 12 and the shuttlewood in front of said chamber has a threader-receiving recess therein which opens to the bobbin chamber and to said delivery eye, the longitudinal sides of said recess being parallel to 20 each other and perpendicular to its bottom. The threader 14 consists of a single piece of cast metal the base portion of which is in the form of a rectangular shaped block, which is adapted to fit closely in said recess and to be secured therein by the usual bolt 13. A thread slot 16 is formed in the threader from end to end thereof, said slot being straight and parallel to the middle longitudinal line of the shuttle and located slightly

25 at one side of said line, and being extended perpendicularly from the top side of the threader and opening into a main thread passage 17, which extends from end to end of the threader in central alignment with the bobbin. The slot 16 thus opens into the upper portion of the passage 17 at one side of the middle thereof. As shown in Figs. 5 and 10, a supplemental thread passage 18 is formed between the passage 17 and the

30 top of the threader, in which the thread may be held at the end of the first pick, this construction being employed when the shuttle is used for fine threads, and a single passage 17¹ is employed in threader 14¹ as shown in Fig. 11, when the shuttle is employed for coarse threads. So far as my invention is concerned, it is immaterial whether the single or double thread passage is employed.

35 A rib portion or bar 20, of somewhat greater thickness than the base portion beneath it, is formed integral with the threader at the opposite side of the thread slot 16 from the shuttle eye, the upper surface of said bar being beveled down to the inner vertical side 21 of the bar, which forms one side of the slot, from the top side of the bar, which is at the level of the upper surface of

40 the shuttle, so as to form a thread deflecting surface 20^a, which decreases in width as it extends from the rear end of the bar 20 to its front end. The bar 20 projects towards the tip of the shuttle beyond the threader base and abuts with a shoulder 10^a on the shuttle. The opposite side of the thread

45 slot from the bar 20 is formed by one side

of a horizontally extending thread retaining finger 22, which extends past the rear portion of a recess 23, and by one side of a beak 24, which extends beyond the threader base and terminates at a substantial distance 70 in the rear of the front end of the bar 20, so that the thread slot opens to the shuttle recess in front of the tip of the beak. The top surfaces of the finger 22 and beak 24 decline to the side edges thereof, so that, as 75 the thread is laid thereon, it will be deflected into the thread slot. The top side of the beak is at a substantial distance beneath the level of the top side of the adjacent portion of bar 20. A thread retaining hook 25 depends from the under side of the beak 24 in front of thread passage 17, the front side of the hook 25 extending perpendicularly from the tip end of the beak and one side thereof being continuous with the edge of the beak 80 which forms a portion of a side of the slot. Said hook 25 also depends in front of the main thread passage 17, or passage 17¹ and terminates slightly above the uppermost portion thereof and directly opposite the 85 middle of the supplemental thread passage 18. The other side edge of the beak from its thread slot side is arranged to deflect the thread to the thread eye and the thread retaining hook 26 also depends from said beak 90 to prevent unthreading after the thread has been drawn into the eye.

A porcelain thread guide 28 is mounted in the threader at the front end of the passage 17 at the side thereof next the eye, so that 100 the thread will be drawn against said guide as it is drawn to the eye. Said guide is fixed in a hole bored in the base of the threader from its under side, the metal at the base of the threader being extended 105 about the guide at its lower end, as shown in Fig. 7, so that its lower portion will be rigidly supported and held against the lateral strains to which a guide thus arranged is sometimes subjected to such an extend as 110 to cause breakage thereof. The lower end of the guide is flush with the bottom surface of the threader, and thus bears firmly on the bottom of the shuttle recess at a substantial distance below the bottom of the 115 thread passage 17.

A transversely concave thread groove 10^b is formed in the tip portion of the shuttle which leads from the threader recess directly in front of the thread passage and extends obliquely to the middle line of the shuttle and terminates close to the metal tip at the end of the shuttle, at which point its middle and deepest portion is at a substantial distance to one side of said middle line 120 and between said line and the eye side of the shuttle. The side 10^b of the groove meets the shoulder 10^a so as to form, for all practical purposes, a continuation of the face 21 of the bar 20, and said side forms a thread 125

deflecting wall which extends obliquely across the middle line of the shuttle to a point approximately in line with the side portion of the thread passage next the shuttle eye, so that as the thread is drawn through the threader slot it will be guided by the side face 21 of the bar 20 to the side 10° of the groove 10^b and as it is drawn down into the bottom of the groove said side 10° will 5 act to deflect the thread laterally beneath the hook 25 to the opposite side of the thread passage from the slot.

The complete threading operation may be described as follows: As the thread is drawn 15 from the bobbin during the first part of the threading operation, it is laid on the upper surface of the threader as it is drawn over the bobbin tip. As the upper surfaces of the threader, at each side of the thread slot 20 16, decline to said slot, the thread will readily fall or be drawn into said slot and be guided to the end of bar 20 and then will be engaged with side 10° of the groove 10^b and will be guided thereby into the groove 10^b 25 thereby deflecting the thread laterally until it falls into the middle or deepest part of the groove, in approximately the dotted line position *x* indicated in Figure 1. As previously stated, the groove 10^b extends 30 obliquely with relation to the center line of the bobbin, so that it terminates at its tip end somewhat at one side of said center line, consequently the position into which the thread falls or is guided is oblique to said 35 center line. As the beak 24 terminates short of the point where the side surface of bar 20 meets the side 10° of the groove, the thread will pass below the end of the beak as it slides down on the upper edge of the side 40 10°, which declines from the top of shoulder 10^a to the shuttle tip as shown in Fig. 3, and, as the thread is, at the same time, deflected laterally towards the bottom of the groove, it will be carried beneath the lower end of 45 the hook 25 by the time it reaches the bottom of the groove, as will be seen from Figs. 1, 2 and 10. When the thread has reached this position, it will have been drawn into either the passage 18 or 17, and, as it has passed beneath the hook 25, when it is pulled back 50 by the action of the shuttle in moving out to make the next pick, if it tends to pass back into the slot 16, it will be caught by said hook. Also if the thread kinks or 55 thrashes about before it is drawn down into the shuttle eye it will be caught by the hook 25, so that unthreading will be prevented. The action of this hook in preventing unthreading by the thrashing or kinking of the 60 thread is assisted by the location of the top surface of the bar portion 20 at the side thereof opposite the hook 25, at a considerable distance, relatively, above the lower end of the hook, so that if the thread falls on 65 this surface of the adjacent top surface of

the shuttle it will be so supported that it cannot pass back beneath the hook.

The specific construction shown is designed for a left hand wound bobbin, so that as the thread is unwound it swings away 70 from the eye side of the shuttle as it passes over the bobbin. If the threader is designed for a right hand wound bobbin, the finger 22 will be arranged on the opposite side of the thread slot from that shown and the entrance to the thread slot will be formed at a corresponding distance from the opposite side of the center line of the bobbin from that shown. So far as the threading action at and beyond the beak of the threader is 80 concerned, the operation would be the same with the type of threader last referred to, as that previously described, except that with a left hand wound shuttle such as shown, the lateral deflection of the thread by 85 the surface 20^a of the rib portion 20 and the side 10° of the groove is somewhat assisted by the lateral swinging of the thread as it is unwound. The threading action is not, however, dependent on the swinging action of 90 the thread due to unwinding, but principally to the arrangement of the oblique side 10° of the shuttle groove with relation to the adjacent portion of the thread slot in the threader and deflecting surfaces of the latter, which cause the thread to be deflected into the thread passage and beneath the hook 25 as it falls, or is drawn into the shuttle groove. The fact that it is not deflected sharply at any point, but only gradually, 95 avoids the possibility of the thread being supported by the deflecting surfaces, instead of being deflected by them, as frequently occurs in certain prior constructions. The more important features of the invention, 100 therefore, reside in the provision of a threader having the straight threading slot, the entrance to which is vertically unobstructed throughout its entire length, and so arranged that, when the thread is drawn 105 from the bobbin over the tip end of the shuttle, it will fall freely into the slot, and the provision of a thread groove in the shuttle tip portion having one side extending practically in continuation with the outer side 110 of the slot obliquely across the thread passage, so as to cause a slight lateral deflection of the thread from the line of the slot as it is drawn over the bobbin tip. With this construction, as the thread falls naturally into the slot and lies therein from end to end, and then is deflected to the bottom of the thread groove 10^b, it will thus be deflected 115 from the straight line, indicated by the dotted line in Fig. 1, extending from the end of the slot next the bobbin to the tip end of the thread groove. As the front end of the inner side of the slot is formed by the side 120 of the hook 25, any pull on the thread tending to draw it straight, or into the position 125

of said dotted line of Fig. 1, acts to draw it against the side of the hook, so that it will slip down past the end of the hook into the first threading position.

5 In the formation of the threader the base portion beneath the thread passage is made of sufficient strength to hold the side portion, on the top of which the bar or rib portion 20 is formed, rigidly, so that a strong 10 support for the shuttle wood which engages it is provided and by extending the bar portion beyond the beak the adjacent portion of the wood is likewise rigidly supported, consequently all possibility that the thread slot 15 will be cramped at the side of the beak is avoided and the shuttle wood will be effectively reinforced at these points.

I claim—

1. An automatically threading shuttle having a bobbin chamber, a slotted, side delivery eye and a threader recess in the tip portion thereof opening to said chamber and eye, a threader in said recess having a centrally aligned thread passage therethru 25 opening to said chamber and the front end of said recess and having a threading slot opening to the top side thereof, and to said passage and extending in approximate parallelism with the passage, said threader having faces declining to said slot at each side thereof, providing a vertically unobstructed top entrance thereto, whereby the thread may be laid therein throughout its 30 length without deflection as it is drawn from said chamber towards the shuttle tip, a thread retaining hook formed with the threader and depending at the tip end of said slot and at the side thereof next the shuttle eye, and the tip portion of the shuttle having a thread groove leading from the front end of said recess, the opposite side of said groove from said eye extending obliquely from the corresponding side of said groove, in effectual continuation thereof, to 35 towards the eye side of the shuttle, so that the slot side of said hook is at one side of a straight line extending from the rear end of the slot to the tip end of the oblique side of said groove.

50 2. An automatically threading shuttle having a bobbin chamber, a slotted side-delivery eye and a threader recess in its tip portion opening to said chamber and eye, a threader in said recess having a thread 55 passage centrally aligned with the shuttle and opening to said chamber and the tip portion of said recess and having a threading slot opening to said passage, said slot being vertically unobstructed and approximately straight and parallel to said passage and somewhat offset from the middle of said passage towards the opposite side of the shuttle from its eye and the upper surface of the threader at each side of the slot 60 declining thereto, said threader having a

depending thread-retaining hook at the tip end of the side of said slot next the middle, and the tip portion of the shuttle having a thread groove leading from the front end of said recess and having its opposite side from the eye leading from the front end of the outer side of the slot in effectual continuation thereof and extending obliquely towards the opposite side of the shuttle, to deflect the thread laid in said slot towards the middle of the passage and beneath said hook. 70

3. An automatically threading shuttle having a bobbin chamber, a slotted, side delivery eye and a threader recess in the tip portion thereof opening to said chamber and eye, a threader in said recess having a centrally aligned thread passage therethru 80 opening to said chamber and the front end of said recess and having a threading slot 85 opening to said passage, said slot having straight sides extending in approximate parallelism with said passage and somewhat offset from the middle thereof towards the side of the shuttle opposite its eye, the side next the middle having a depending thread-retaining hook at its tip end and the opposite side being extended a substantial distance beyond said hook and thread deflecting faces being formed on the top side of the threader which decline to said sides at each side, so that the top entrance to the slot is vertically unobstructed, and the tip portion of the shuttle having a thread groove therein the side thereof opposite the eye extending from the adjacent end of the corresponding side of said slot obliquely across the line of said passage, so that when the thread is laid in said slot and in said groove it will be bent at an angle as it is 90 drawn against the side of said hook. 95

4. An automatically threading shuttle having a bobbin chamber, a slotted side-delivery eye and a threader recess in the tip portion thereof opening to said chamber and eye, a threader secured in said recess having a centrally aligned thread passage therethrough and a straight threading slot therein to which its top surfaces decline, at each side, to form an unobstructed top entrance thereto throughout its length, said slot being extended in approximate parallelism with said passage and opening thereto throughout the length thereof, a longitudinally extending beak formed with the threader and having a thread-retaining hook depending therefrom at its tip end, one side of said beak and hook forming one side of the tip end portion of said slot, the threader portion forming the opposite side of said slot extending longitudinally beyond the tip end of the beak and providing a thread directing surface, and the tip portion of the shuttle having a thread groove 110 opening to said recess in line with said pas. 115

sage and extending obliquely therefrom to one side of the middle line of the shuttle, one side of said groove being arranged in approximate continuation of said thread 5 directing surface and extending obliquely therefrom across said middle line, to deflect the thread transversely of the shuttle beneath said hook as it is drawn into said groove.

10 5. An automatically threading shuttle having a bobbin chamber, a slotted side delivery eye and a threader recess opening to said chamber and eye, a rigidly formed threader secured in said recess and having a centrally aligned thread passage there- 15 through and a straight threading slot leading from the top side thereof to said passage throughout its length with the top surfaces of the threader declining to said slot at each side thereof, so that the entrance thereto is vertically unobstructed, a beak formed with the threader having one side thereof forming one side of said thread slot and having a thread retaining hook depend- 20 ing from its tip end at the end of said side, a bar formed with the threader at the op- 25 posite side of the slot from said beak pro- 30 jecting towards the shuttle tip beyond the tip of the beak and having a thread direct- 35 ing surface forming a portion of the side of the slot, and the tip portion of the shuttle having a shoulder with which the end of said bar abuts and having a thread groove ex- 40 tending obliquely to the center line of the shuttle from said recess at the end of said thread passage to the shuttle tip, one side of said groove extending from the end of said shoulder, in position to form a con- 45 tinuation of said thread directing surface, and to provide an oblique surface arranged to deflect the thread laterally beneath said hook and into said passage as it is drawn through said slot and into said groove.

5. An automatically threading shuttle having a bobbin chamber, a slotted side delivery eye and a threader recess in the tip portion thereof opening to said chamber and eye, a threader in said recess having a centrally aligned thread passage and a straight-sided thread slot extending in parallelism with said passage and opening directly thereto and to the top side of the threader so that the top entrance to said slot is vertically unobstructed throughout 55 the length thereof, a beak formed with the threader having a side face extending to its tip end and forming one side of said slot and having a top face declining to said side face, a thread retaining finger depending from the under side of the beak at its tip end, opposite the end of said thread passage, a bar formed with the threader having a side face forming the opposite side of said slot and a top face declining thereto, said bar 60 being extended towards the shuttle tip be-

yond the tip of the beak and the shuttle tip portion having a shoulder with which the end of said bar abuts and having a thread groove extending from said recess in position to receive the thread as it is drawn 70 through said passage over the shuttle tip, one side of said groove extending from the end of said shoulder obliquely to the side face of said bar and in substantial continuation thereof and in position to deflect the 75 thread laterally beneath said hook as it is drawn into said groove.

7. An automatically threading shuttle having a bobbin chamber, a slotted side-de- 80 livery eye and a threader recess in the tip portion thereof opening to said chamber and eye, a threader in said recess having a cen- 85 trally aligned thread passage and a straight- sided vertically unobstructed thread slot ex- 90 tending in parallelism with said passage and opening thereto and to the top side of the threader throughout the length thereof, a beak formed with the threader having a side face extending to its tip end and forming one side of said slot and having a top face 95 declining to said side face, a thread re- 100 taining finger depending from the under side of the beak at its tip end, opposite the end of said thread passage, a bar formed with the threader having a side face forming the opposite side of said slot and a top face declining thereto, said bar being extended towards the shuttle tip beyond the tip of the beak 105 and having the top face thereof opposite and beyond the tip of the beak at a substantially higher elevation than the top surface of the tip of the beak, and the shuttle tip portion having a thread groove arranged to receive the thread as it is drawn through said passage, one side of which is 110 arranged to form a substantial continuation of the side face of the bar and to extend therefrom obliquely towards the opposite side of the shuttle to deflect the thread laterally beneath said hook as it is drawn towards the shuttle tip.

8. An automatically threading shuttle having a bobbin chamber, a slotted side de- 115 livery eye and a threader recess in its tip portion opening to said chamber and eye, a 120 threader in said recess having a thread pas- 125 sage in central alignment with the bobbin when in position in said chamber and a straight thread slot extending vertically from its top side and opening into said passage from end to end at one side of the middle thereof, a beak formed with the threader having one side edge forming one side of said slot and having a thread re- 130 taining finger depending from its tip end in front of the front end of said passage, a bar formed with the threader having one side forming the opposite side of said slot, the top surfaces of said beak and bar de- clining to said sides to direct the thread into

said slot, and the top portion of the shuttle having a transversely concave thread groove opening to said recess in front of said thread passage and extending obliquely towards the shuttle tip, one side of said groove being arranged to extend obliquely from the front end of the side of said bar transversely of the line of said thread passage to deflect the thread laterally beneath said hook as it is drawn through said slot into said groove.

9. An automatically threading shuttle having a bobbin chamber, a slotted side delivery eye and a threader recess in its tip portion opening to said chamber and eye, a threader in said recess having a centrally aligned thread passage and a straight-sided threading slot, said slot having a vertically unobstructed opening to the top side of the threader throughout the length thereof and extending in parallelism with said passage

and opening thereto, a beak formed with the threader having one side edge forming one side of the slot and having a thread retaining finger at its tip depending therefrom in front of said passage, a bar formed with the threader having a side forming the opposite side of the slot from the beak and the tip portion of the shuttle having a thread groove opening to said recess opposite the front end of said passage and slot and extending adjacent the tip of the shuttle, said groove having one side thereof forming an effectual continuation of the side of said bar and extending obliquely thereto transversely of the line of said passage, to deflect the thread beneath said hook as it is drawn into said groove.

In testimony whereof, I have signed my name to this specification.

HENRY L. BONNEY.
